UNITED STATES PATENT OFFICE.

GEORGE CLAYTON REID, OF BROOKLYN, NEW YORK, ASSIGNOR TO AMERICAN CAN COMPANY, OF NEW YORK, N. Y., A CORPORATION OF NEW JERSEY.

CONTAINER.

Application filed July 14, 1924. Serial No. 725,811.

My invention relates to containers of sheet metal wherein score lines are provided to permit tearing away of a part to open the container and provide access to its contents.

Containers of this sort have in the past been provided with various arrangements of score lines permitting, for example, removal of part or substantially all of an end of the container and as a further example removal of a strip encircling the container. Although the invention will hereinafter be described as embodied in a can from which an end is to be torn away along the score lines, it will be readily manifest that the invention may with equal facility be embodied in containers of other character and having other arrangement of scoring.

Prior to my present invention scoring in tin and other sheet metal containers has been accomplished by merely cutting part way through the metal along the lines of score, care being exercised to limit the depth of cut throughout the length of the score lines to leave sufficient metal to provide the necessary strength of sheet. This circumstance and the further circumstance that sheet metal varies in thickness in successive sheets and even in the same sheet has rendered necessary the use of a key or other special tool to tear along the score lines for the removal of the part set-off by them. Moreover, when, as of course happens upon occasion, the scoring is deeper than is safe for the particular sheet of tin or the particular section of the sheet of tin, the cutting passes through the metal and hermetic sealing of the container rendered impossible.

It has also been proposed to cut through the tin at intervals, and form a V-groove at such line of cutting and lay a wire in said groove and cover the wire with solder, which was an expensive construction and not satisfactory, because if the wire were pulled towards the line of partial cutting of the sheet metal it would not sever the solder, and if it should be pulled toward the solder it would leave the sheet metal intact. My container can be opened without the use of any wire, and the thin remaining metal at the bottom of the scoring groove, and also the filling solder or other weak material, can both be torn through at once, with slight force, and with almost any implement, even with a lead pencil.

My invention has for its principal object

the provision of scoring in a container, which in the finished product will not require dependence solely upon the strength of the metal between the base of the cut and the opposite face of the sheet and which will permit of hermetic sealing of said container even where there is complete severance throughout portions of the score lines themselves.

My invention has for a further and highly important object the provision of a container of sheet metal from which a part may be removed along the score lines without the use of a key or other special tool.

My invention contemplates the provision of score lines of depth in excess of that at present considered safe and the filling in of said score lines with solder or other material of low tensile strength adapted to adhere to the metal to close said score lines against possible leakage and to provide sufficient strength to permit safe working of the scored part to form the can.

My invention contemplates both a new product and a new process for producing the same.

Numerous other objects and advantages of the invention will be apparent as it is better understood from the following description, which, taken in connection with the accompanying drawings, discloses a preferred embodiment thereof.

Referring to the drawings,

Figure 1 shows a perspective view of the metallic container provided with a score or weakened line in its top or cover;

Fig. 2 is a fragmental sectional view of a container cover and scoring die members, the view illustrating the formation of the channel within one face of the cover;

Fig. 3 illustrates a cross section of a container cover and a fragmental portion of a solder applying roller;

Fig. 4 is a fragmental enlarged view of the container illustrating a weakened section filled with solder;

Fig. 5 is an elevation of a container and its cover, a portion being broken away to more clearly illustrate the parts, the view showing the piercing of the cover by means of a sharp instrument;

Fig. 6 is a cross sectional fragmental view of the upper part of a container and its cover, illustrating the removal of the area defined by the score lines;

Fig. 7 is a cross sectional fragmental view of the upper view of a container and its cover after its central part has been removed.

5 Referring more in detail to the drawings, numeral 11 designates any suitable container body provided with a bottom end 12 and a cover 13, the parts being secured together in any suitable manner, such as the
10 ordinary double seam illustrated at 14. The cover 13 is provided with a scored or weakened line which is adapted to be broken in the opening of the container. For the purposes of illustration said score line is
15 formed by a channel 15 cut on the underside of the face of the cover, although such a line could readily be formed in any other part of the container. This cut is made in any well known manner, for example by
20 means of a scoring die 16 pressing against a backing plate 17, as illustrated in Fig. 2. The channel 15 is then filled with solder 18 applied in any suitable manner, for example by a roller 19 rotating against the channel portion 15 of the cover and causing the solder to flow into said channel and to completely fill the same.

When it is desired to remove the cover any sharp instrument, for example a pointed ice pick 20, is inserted into the weakened line and by an upward leverage of the opening tool the central portion 21 of the cover is lifted from the cover 13, this being easily done by reason of the low tensile strength
30 of the solder, see Fig. 6. After removal of the central portion 21 of the container 13, there is left an opening 22 having a clean-cut smooth edge as clearly illustrated in Fig. 7.

40 It will be manifest that the score cut does or may extend substantially through the container end or wall in which it is provided, the solder filling giving the necessary strength and preventing leaking.

45 It will thus be seen that my invention provides a sheet metal container a wall of which is formed with a score line which is sufficiently deep to offer small resistance to tearing, and which is filled with a substance
50 which offers small resistance to tearing, and which when solder is used, takes the place of the scored away metal so as to partly and sufficiently restore the strength which the sheet metal had before scoring.

55 It is thought that the invention and many of its attendant advantages will be under-

stood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The method of providing a removable section in an hermetic metallic container, which consists in scoring and reducing the thickness of the metal of the container at the portion surrounding the removable section, building up said section to substantially its original thickness by placing thereon and uniting therewith a metallic material of lower tensile strength than the tensile strength of the metal of the container to permit easy opening thereof.

2. The method of providing a releasable section in a sheet metal container, which consists in forming a score line around the section of the container which is to be released for opening the same, said score line not having associated therewith any wire or ripping instrumentality, said score line being sufficiently deep to offer small resistance to tearing, and then filling said score line with a substance which offers small resistance to tearing.

3. A sheet metal container a wall of which is formed with a relatively deep continuous score line having two functions, to contain soft metal and to weaken the wall for the purpose of tearing leaving a thin integral connection between the parts of the wall and adapted to be ruptured to release a part of the wall for opening the container, said score line being filled with a relatively soft metal, and said score line not having associated therewith any wire or ripping instrumentality.

4. A sheet metal container a wall of which is formed with a deep continuous score line leaving a thin integral connection between the parts of the wall and adapted to be ruptured to release a part of the wall for opening the container, said score line being filled with a relatively soft metal and not having associated therewith any wire or ripping instrumentality, said wall being formed with a depression at said score line whereby an instrument is guided to the line to begin the rupture of the wall along said line.

GEORGE CLAYTON REID.
